US00D810176S

(12) **United States Design Patent** (10) **Patent No.:** **US D810,176 S**
Zheng et al. (45) **Date of Patent:** **** Feb. 13, 2018**

(54) **HANDLE COMPONENT**

(71) Applicant: **SZ DJI Osmo Technology Co., Ltd.,**
Shenzhen (CN)

(72) Inventors: **Haibin Zheng**, Shenzhen (CN); **Min Kim**, Shenzhen (CN)

(73) Assignee: **SZ DJI Osmo Technology Co., Ltd.,**
Shenzhen (CN)

(**) Term: **15 Years**

(21) Appl. No.: **29/588,371**

(22) Filed: **Dec. 20, 2016**

Related U.S. Application Data

(63) Continuation of application No. 29/561,458, filed on Apr. 15, 2016.

(51) **LOC (11) Cl.** **16-01**

(52) **U.S. Cl.**

USPC **D16/219**

(57) **CLAIM**

The ornamental design for a handle component, as shown and described.

DESCRIPTION

FIG. 1 is a top front perspective view of a handle component showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the handle component that form no part of the claimed design. The dot-dash broken lines in the figures show boundaries that form no part of the claimed design.

1 Claim, 6 Drawing Sheets
